UNITED STATES PATENT OFFICE.

OLIVER C. ALLEN, OF CENTER TOWNSHIP, HANCOCK COUNTY, INDIANA.

SUSPENSION-FENCING.

1,109,312.

Specification of Letters Patent. Patented Sept. 1, 1914.

Application filed July 19, 1913. Serial No. 779,969.

To all whom it may concern:

Be it known that I, OLIVER C. ALLEN, a citizen of the United States, residing in Center township, in the county of Hancock and State of Indiana, have invented a new and useful Suspension-Fencing, of which the following is a specification, reference being had to the accompanying drawings and to the letters and figures of reference 5 marked thereon.

This invention relates to the type of fencing that is designed for continuing field or divisional fencing across streams, ravines or ditches through which water may flow 10 either continuously or periodically, the invention having reference more particularly to fencing that is suspended on supports located on solid and relatively high ground, such as the banks of streams or ravines, and 15 adapted to swing so as to afford ample 20 clearance for the passage of water.

An object of the invention is to provide improved suspension fencing of such construction as to be adapted to extend across 25 a stream or low ground through which water may flow at times, especially during flood seasons, and which shall not retard the current of the water so as to cause washing out of the bed of the stream, and which 30 shall be suspended clear of the bed so as to not require support in the stream or between the banks that would be liable to 35 collect trash or rubbish from the current of the water.

35 A further object of the invention is to provide improved sectional fencing adapted to be swingingly suspended and be sufficiently flexible to permit timber or trash to pass under the fencing during floods.

40 A still further object of the invention is to provide improved means for supporting suspension fencing in a reliable manner so as to not be liable to become seriously deranged and necessitate troublesome repairs 45 in use under the severe conditions to which the fencing may be subject.

With the above mentioned and other objects in view, the invention consists in suspension fencing comprising improved fence 50 panels connected together in a novel manner, improved supporting means and improved suspending means for the panels; the invention consisting further in the parts

and combinations and arrangements of parts as hereinafter particularly described 55 and further defined in the accompanying claims.

Referring to the drawings, Figure 1 is a cross section of a stream illustrative of the purpose and function of the invention 60 which is shown in elevation looking upstream; Fig. 2, a sectional elevation on the line A A in Fig. 1; Fig. 3, a fragmentary section on the line B B in Fig. 1; Fig. 4, a section on the line C C in Fig. 2; Fig. 5, a 65 fragmentary elevation showing two connected fencing panels; Fig. 6, a section on the line D D in Fig. 5 on an enlarged scale; Fig. 7, a section on the line E E in Fig. 6; Fig. 8, a horizontal section on the line F F 70 in Fig. 5; Fig. 9, a fragmentary elevation illustrating the manner of connecting the panels with the suspension cable; and Fig. 10, an elevation of a slightly modified arrangement of cable supporting means. 75

Similar reference characters in the different figures of the drawings indicate corresponding elements or features of construction hereinafter referred to in detail.

In the drawings, the numeral 1 indicates 80 the bed and 2 the surface of the water of a stream; 3 and 4 indicating the banks of the stream, or the higher solid ground on either side of a gully or ravine.

In practically carrying out the objects of 85 the invention, two masts or posts 5 and 6 of suitable height are provided and set in the banks respectively sufficiently far back from the stream to be firmly supported uprightly, being arranged so as to be on the 90 line of a field or divisional fence. Two eye-bolts 7 and 7' are connected to the upper portions of the masts respectively and suitable bracing cables or rods 8 and 8' are respectively connected thereto and provided with 95 turnbuckles 9 and 9' respectively to which anchor cables or rods 10 and 10' are connected, the latter extending into the ground obliquely and being connected to suitable anchors 11 and 12 respectively that are buried 100 in the ground at suitable distances back from the stream beyond the masts, for bracing and preventing the masts from being pulled over toward the stream. Two other eye-bolts 13 and 13' are connected also to the 105 masts 5 and 6 respectively, and a bracing

100
105

cable or rod 14 or 14' is connected to each eye-bolt and extends in up-stream direction and is provided with a turnbuckle 15 to which an anchor cable or rod 16 is connected, the latter extending obliquely in the ground and is connected to a suitable anchor block 17 that is buried in the ground. The two masts 5 and 6 are provided respectively with two thimbles 18 and 18' that are set horizontally in suitable openings at a suitable height above the ground, and a suspension cable 19 is arranged so as to extend through the two thimbles and across the depression of the ground between the masts, the end portions of the cable extending downward obliquely toward the anchoring devices. The ends of the cable are provided with turnbuckles 20 and 20' respectively to which anchor cables or rods 21 and 21' are connected, the latter being connected respectively to the anchor devices 11 and 12. The weight supported by the cable being considerable, the tendency would be to cause the wood of the masts to split, this tendency, however, being counteracted by the thimbles which practically increase the bearing area of the cable. The two masts 5 and 6 are provided also with two other thimbles 22 and 22' respectively at a suitable distance [30] above the suspension cable and a stay-wire or cable 23 is placed therein and is provided on its ends with turnbuckles 24 and 24' that are connected to anchor rods or cables 25 and 25' respectively, the latter being connected to the anchor devices 11 and 12 respectively. The middle portion of the wire or cable 23 is secured to the middle portion of the cable 19 by means of a suitable binding device 26, the device being approximately midway between the two masts so that the stay-wire or cable supports the suspension cable intermediately of the masts. In case the span is of such length as to be insufficiently supported by one stay-rod or [45] wire, additional devices are provided comprising preferably two eye-bolts 27 and 27' connected respectively to the two masts 5 and 6, and cables or rods 28 and 29 are connected respectively to the eye-bolts and also 50 to the suspension cable 19 at suitable distances from the masts.

The line of fencing leading onto the opposite banks of the stream have terminal end panels 30 and 31 that are connected to the masts 5 and 6 respectively. It will be understood that, if desired, each eye-bolt may be placed in a thimble 32 set in the mast, and it will be understood also that each eye-bolt includes a nut 33 and a washer 34 interposed between the nut and the mast or post, so that in some cases the slack may be taken up by turning the nut so as to move the eye-bolt in the mast.

In case there is level ground between a mast and the slope of the bank, a horizontal

panel of fencing of suitable length is provided and comprises upright end members or posts 35 and 36 and a suitable number of horizontal rails or stringers 37, the end members being provided with suitable suspenders 38 and 39 that are connected to the suspension cable 19. The end member 35 is connected to the mast 5 by means of wire bands 40 and 41 suitably spaced apart, the bands permitting the panel to have a slight twisting and hinge-like movement on the mast. Another panel that is adapted to conform to the slope of the bank is provided and comprises end members 42 and 43 that are arranged vertically, and a suitable number of rails or stringers 44 that are secured to the end members at oblique angles thereto so as to be substantially parallel with the face of the slope, and if the panel is required to be of considerable length, a "center-post" or auxiliary supporting member 45 is connected in vertical arrangement to the rails or stringers. Suspenders 46, 47 and 48 are connected respectively to the members 42, 43 and 45 and also to the suspension cable 19, the suspenders being of different length. The end member 42 is connected to the end member or post 36 by means of two wire bands 49 and 50 that permit slight twisting and hinge-like movement of the respective panels. On the opposite bank a horizontal panel may not be required between the mast and the slope so that a similar oblique angled fence panel may be used as illustrated, the panel comprising end members or posts 42' and 43', a suitable number of relatively inclined rails 44' and a supporting center bar 45', the panel being provided with suspenders 46', 47' and 48' of different lengths which are hung on the cable 19, the end member 42' being connected directly to the mast 6 by means of wire bands 40' and 41'. Preferably a barbed wire 51 is connected to the lower portions of the end members 42 and 43 and also to the member 45 below the lower one of the horizontal rails 44 to prevent the passing of hogs under the panel, the opposite panel being similarly provided with a barbed wire 51'. A suitable number of horizontal panels are provided and of such lengths as to complete the span between the oblique angled or slope panels, and each one comprises two end members or post 52 and 53, a suitable number of rails or stringers 54 secured to the end members, and a center support or post 55 secured to the middle portions of the rails. The end members are provided with suspenders 56 and 57 respectively, and the center support with a similar suspender 58, the suspenders being of suitable length so as to support the panels with the lower rail slightly above the surface of the water of the stream at low stage. Two wire bands [130]

59 and 60 connect one end member of one of the panels to the end member 43 of one of the slope panels, the connection being non-rigid so that there is slight flexibility and 5 may be slight hinge-like movement at the connection. Each of the panels preferably has a barbed wire 61 connected to the lower portions of the upright members so as to be under water and prevent animals from passing under the panel. The end member 52 10 of a center panel is connected to the end member 53 of an adjacent panel by means of wire bands 62 and 63, and similar bands 64 and 65 connect the opposite end member 15 53 of the panel to the member 52 of an adjacent panel. The vertically arranged members of the panels preferably extend upward a considerable distance beyond the upper rail of the panels so that the center of 20 gravity of the panel is relatively low, the suspenders being connected to the upper ends of the members so that the tendency of the panel is to hang plumb and offer considerable resistance to counteract the tendency 25 of the current to float and raise the panel toward horizontal position. In some cases, if desired, a suitable number of slats or pickets 66 are secured in vertical arrangement to the rails of the panel, in which case 30 only a top and a bottom rail may be desired without any intermediate rail.

In order to reliably connect the suspenders to the upper ends of the vertical members of the panels, which preferably are wooden, 35 a bolt 67 is inserted through the upper portion of the vertical member, as 52 and 53, the bolt having a head 68 on one end and a washer 69 interposed between the head and the member, the opposite end of the bolt 40 having a nut 70 thereon and a washer 71 interposed between the nut and the member. A hole 72 is bored in the member transversely to and immediately below the bolt. The lower portion of the suspender or 45 hanger, as 57 is passed through the hole and bent over to form a loop 73 which has contact with the bolt, the latter preventing the wire loop from splitting the wood, the end of the wire of which the suspender is 50 formed being brought up and connected to the main portion of the suspender by means of a twist or coil 74.

The middle portion of the suspension cable 19 being more or less depressed or 55 sagged by the weight of the fencing, the suspenders are suitably connected to the cable so as to prevent them from slipping toward the middle portion of the cable and without rigidly securing the suspenders to 60 the cable, and preferably the wire of each suspender is brought twice around the cable so as to form a coil or double loop 75 or 76, the end of the wire being connected to the main portion of the suspender in the form 65 of a twist or coil 77. A piece of small wire

cable having two strands 78 and 79 is suitably employed, one end portion of the piece being untwisted and the wires brought around the cable 19 to form a loop 81, the wires of the opposite end portion being brought 70 around the cable to form a loop 81, and the wires of the respective ends are brought together in the form of twists 82 and 83 respectively so as to bind the wires tightly to the cable 19 on opposite sides of the suspenders, so that a tie 84 is formed that extends or reaches over the coil 75 or 76 or across both coils when arranged in relatively close order, the tie being firmly secured on opposite sides of the suspenders, which, as 80 will be seen especially in Fig. 9, are permitted to swing on the cable 19 but are prevented from moving to any appreciable extent longitudinally of the cable.

In some cases the suspension cable 19 85 may be otherwise reinforced, a sample of which is illustrated in Fig. 10. Anchor rods 85 and 85' may be secured to anchor blocks 11' and 12', buried in the ground, and the rods of turnbuckles 86 and 86' are connected 90 to the ends of the cable 19 and to the anchor rods, the cable extending through the masts 5 and 6, and stay-rods or cables 87 and 87' are connected to the eye-bolts 7 and 7' and also to the anchor rods. The rods of turnbuckles 88 and 88' are connected also to the anchor rods 85 and 85' and to a pair of relatively short cables 89 and 89' that extend through the upper portions of the masts and to which two cables or flexible rods 90 and 91 of equal length are connected. The cable 90 is secured by means of a clamp 92 to the cable 19 between the middle portion of the latter and the mast 5, the remaining cable 91 being secured to the cable 19 by means of a clamp 93 between the mast 6 and the middle portion of the cable 19.

It will be understood that although the upper band 62 rests upon the upper rails 54 of the panels and the lower band 63 rests 110 upon the barbed wire 61 for support, the bands, being slightly loose on the end members, may be otherwise prevented from sliding down the end members of the panels. It will be understood also that various modifications may be fairly made within the scope 115 of the accompanying claims.

In practical use, the suspension fencing normally hangs vertically and forms a continuation of the line fencing adjacent to the stream or ravine and offers little or no obstruction to the flow of the water at low or moderately high stages. When flood stages occur the water forces the fencing to swing slightly down stream as indicated by 120 dotted lines in Fig. 2, the loose connections between the panels and the sloping end panels permitting slight flexibility so that the suspended panels collectively assume the form of a curve, the middle portion of 125 130

- 2
which, however, is relatively flat, the normally vertical plane of the panels becoming inclined by the force of the water as the water rises, so that rubbish or debris readily 5 glides under the panels, the barbed wire still remaining under the surface of the water and preventing the passage of animals, but permitting the force of the current to force the rubbish under the wires.
- 10 Having thus described the invention, what is claimed as new is—
1. Suspension fencing including two upright masts, a suspension cable supported by the masts, a plurality of fence panels 15 each comprising vertical end members and also rails, the rails of the terminal panels being inclined relatively to the end members, the rails of the remaining panel or panels being horizontal, and suspenders differing in length connected to the end members of the respective panels and also to the cable, the shorter suspenders being connected to the terminal end members of the terminal panels.
- 20 2. Suspension fencing including two upright masts, two cables extending movably through the two masts, one cable above the other in each mast, the end portions of the upper cable extending downward convergently to the end portions of the lower cable beyond the masts respectively, one end portion of each cable being provided with a tension adjuster, an anchor block operatively connected with the tension adjusters, an anchor block operatively connected with the opposite end portion of the two cables, two eye-bolts connected to the two masts respectively, each between the two cables, two stays connected to the two eye-bolts respectively, one of the stays being operatively connected with one of the anchor blocks, the remaining stay being operatively connected with the remaining one of the anchor blocks, a device connecting the two cables together 35 between the masts, and fencing supported by the lower one of the cables.
3. Suspension fencing including two upright masts, each mast having two thimbles therein arranged one above the other, two anchor blocks arranged beyond the masts respectively, a suspension cable extending movably through the lower thimbles and operatively connected with the two anchor blocks, each end portion of the cable being 40 provided with a tension adjuster, a stay wire extending movably through the upper thimbles and operatively connected also with the two anchor blocks, each end portion of the stay wire being provided with a tension adjuster, a binder securing the suspension cable to the stay wire between the masts, two anchoring links connected to the two anchor blocks respectively, one link being connected with one of the masts between the two 45 thimbles and the other link with the re-

mainning mast between the two thimbles, each link being provided with a tension adjuster, and fencing supported by the suspension cable.

4. Suspension fencing including two upright masts, a suspension cable supported by the two masts, a plurality of fence panels each comprising vertical end members and also rails, the rails of two of the panels being inclined relative to the end members, the rails of the remaining panels being horizontal, the panels being arranged end to end, one of the panels that has inclined rails being arranged between two of the panels that have horizontal rails, suspenders connected to the end members respectively of the several panels and also to the cable, a number of the suspenders that are connected to the end members of the terminal panels being shorter than the remaining suspenders, bands loosely connecting the adjacent end members of adjacent panels together at the lower and higher portions of the members, and bands loosely connecting the terminal end members of the terminal panels respectively to the masts.

5. Suspension fencing including two uprightly supported masts, each mast having a thimble therein, a suspension cable supported by the masts within the thimbles and anchored at its ends beyond the masts, the cable being movable in the thimbles and provided with a tension adjuster, a plurality of fence panels loosely connected together end to end, the two terminal ones of the panels having inclined rails extending upward toward the masts, the remaining panels having relatively horizontal rails, all the panels having each a plurality of relatively vertical members that extend upward beyond the rails, and a plurality of suspenders connected to the suspension cable and also respectively connected to the upper portions of the vertical members of the panels, the suspenders that are in proximity to the masts being shorter than the others.

6. Suspension fencing including two uprightly supported masts, the upper portion of each mast having a thimble therein, two eye-bolts connected to the masts respectively, one above each thimble, two stays connected to the eye-bolts, one to each, and anchored at their ends beyond the masts, respectively, each stay being provided with a tension adjuster, a suspension cable extending through the two thimbles and anchored at its ends, a plurality of fence panels having upwardly projecting members and arranged end to end, bands connecting the adjacent end portions of the panels together, bands connecting the ends of the terminal panels to the masts, and suspenders connected to the suspension cable and respectively to the projecting members of the panels.

7. In suspension fencing, the combination of a supported suspension cable, a fence panel, a plurality of suspenders connected to the panel and having each a coil embracing the cable, and a tie comprising wires twisted together and extending over the coil of the suspender, the two end portions of the wires being looped about and fixedly secured to the cable on opposite sides respectively of the coil.

8. In suspension fencing, the combination of a supported suspension cable, a plurality of fence panels having adjacently arranged vertical end members, each end member having a suspender connected thereto and also to the cable, and a tie embracing two adjacent ones of the suspenders and having two end portions fixedly secured to the cable on opposite sides respectively of the two suspenders.

9. In suspension fencing, the combination of a supported suspension cable, a fence panel comprising relatively vertical members and transverse rails secured to said members, the upper portion of each one of the vertical members of said panel having a bolt secured therein and also a hole extending transversely to and immediately below and intersecting the bolt, and a plurality of suspenders connected to the cable and having loops respectively extending through the holes and in contact with the under side of the bolts respectively.

10. In suspension fencing, the combination of a supported suspension cable, a plurality of fence panels normally arranged uprightly and end to end below the cable, each panel comprising a plurality of vertical members and rails secured to the vertical members, and also a barbed wire secured to the vertical members below the lower one of the rails, bands embracing the adjacent end members and resting upon the upper rails, bands embracing the said end mem-

bers and resting upon the barbed wires, and a plurality of suspenders connected to the cable and also to the vertical members respectively of the panels.

11. In suspension fencing, the combination with the ends of two lines of fencing, of two masts set uprightly at the ends of the two lines respectively, two stays connected to the two masts respectively and extending downward obliquely on planes approximately at right angles to the lines of fencing, each stay being provided with a tension adjuster, means for anchoring the stays, two anchored stays extending approximately parallel with said lines and connected respectively to the two masts below the first described stays, an anchored suspension cable extending movably through the two masts, a tension adjuster for the cable, cable supporting means supported by the masts above the stays and connected to the suspension cable between the masts, and a plurality of fence panels loosely connected together and to the masts and swingingly suspended to the suspension cable.

12. In suspension fencing, the combination of two uprightly supported masts, an anchored suspension cable adjustably supported by the two masts and provided with a tension adjuster, a plurality of fence panels arranged end to end between the masts, two of the panels having relatively oblique-angled end members and rails, suspenders connected to the suspension cable and to the respective panels and swingingly supporting the panels, bands connecting the adjacent ends of the panels together, and bands connecting the terminal panels to the masts.

In testimony whereof, I affix my signature in presence of two witnesses.

OLIVER C. ALLEN.
